UNITED STATES PATENT OFFICE.

MARTIN L. NELSON, OF PARK RIDGE, ILLINOIS, ASSIGNOR, BY MESNE ASSIGNMENTS,
TO AUTOMATIC ELECTRIC INC., OF CHICAGO, ILLINOIS, A CORPORATION OF DELA-
WARE.

DIRECTOR.

Application filed June 13, 1924. Serial No. 719,719.

The present invention relates to directors, or registering, translating, and sending apparatus, for use in controlling the establishment of connections in automatic telephone systems. An automatic telephone system in which directors are used is described and illustrated in my prior joint application with R. G. Richardson, Serial No. 547,866, filed March 29, 1922.

In the prior application referred to the director is considered from a circuit standpoint, and its operation and functions are explained, but in the instant case the director is considered from a structural angle, as a piece of apparatus or mechanism. A complete director comprises a considerable number of parts, including a number of separate switching devices and distributing frames, and it has been found desirable, in order to simplify the wiring and to provide for easy substitution when necessary, to assemble all the various parts together as a single unit. The object of the present invention, therefore, is the organization of the different parts of a director so that they may constitute a single physical piece of apparatus, which may be installed and operated like any of the other units of a Strowger system.

The various features of the invention are more fully explained in the following detailed description, reference being had to the accompanying drawings, in which—

Fig. 1 is a front view of a director constructed according to the invention;

Fig. 2 is a rear view;

Fig. 3 is a section on the line A—A, Fig. 2, with the distributing frame turned outward on its hinges so as to show the back side thereof;

Fig. 4 is a section on the line B—B, Fig. 1;

Fig. 5 is a side view of the test jack assembly shown from the front in Fig. 1; while

Fig. 6 is a fragmentary view showing the construction of a shelf or rack upon which the directors are mounted.

The essential parts of a director are an office register, a plurality of digit registers, usually four, a so-called master digit controller, or steering switch, a sending switch, a sequence switch, a plurality of relays, the

number varying with the particular circuit used, and a distributing frame, together with the necessary wiring and cabling. All these various parts are assembled and mounted on a single frame so as to constitute a single unitary piece of equipment.

The frame comprises two pieces of angle iron 2 and 3, best seen in Figs. 2, 3 and 4, and a metal plate 4, rectangular in shape, which is secured to the two pieces of angle iron by means of machine screws as shown. The upper edge of the plate is bent at right angles so that it extends to the rear to a point just beyond the rear edges of the angle irons. The dimensions of the face of the plate are approximately 15 inches by 18 $\frac{1}{4}$ inches.

On the front of the frame plate are mounted all the principal parts of the director except the distributing frame, which is on the back. These parts will now be pointed out and described so far as is necessary.

The devices on the front of the frame, Fig. 1, will be considered first. Of these, the office register is at the left where it is indicated by reference letter J. The office register is a standard vertical and rotary Strowger switch, having four wipers, and is mounted on the face of the frame plate by means of two machine screws 5 and 6, Fig. 3. The holes in the frame through which the screws pass are bushed and insulating fibre strips 7 and 8 are inserted in order to insulate the switch frame from the plate. An opening 9 in the frame plate is provided to permit adjustment of the rotary magnets of the switch. Another opening 10 is provided in order to pass the bank cables to the rear of the frame. Two fibre strips 11 and 12, seen best in Fig. 2, fit tightly around the cables and close opening 10.

The five small switches at the top and to the right, are small rotary switches of the type known in the art as a minor switch. A switch of this type has a short shaft carrying one or more wipers, a driving magnet which rotates the shaft by means of an ordinary ratchet and pawl mechanism, and a release magnet which controls the ratchet retaining pawl. It also has an arcuate bank of ten contacts or sets of contacts, and may have one or more pairs of off-normal springs.

These switches are mounted on the frame plate similar to the way in which relays are mounted, as may be seen from Figs. 1 and 4. The latter figure shows the means 5 for mounting the first minor switch M, consisting of two machine screws 14 and 15, passing through the frame plate and entering the switch frame. Figure 1 shows the drilling of the frame for the switch magnet 10 terminals and mounting screws, attention being directed to the vacant or extra space to the right of minor switch M⁴. Holes 17, 18, 20, and 21 are provided to pass the terminals, holes 16 and 22 are for the mounting 15 screws such as 14 and 15, while hole 19 provides room for the head of the screw by which the driving magnet is held in the switch frame. Just behind the switch banks a large rectangular opening 23 is provided 20 through which the bank wires (not shown) pass to the rear. As to the functions of the switches shown, the first one at the left, M, is the master digit controller, or steering switch, by means of which the register control 25 circuit is associated with the different register switches successively. The other four minor switches, M' to M⁴, inclusive, are the four digit registers.

Just to the right of the bank of the office register are mounted two switches of the well known rotary line switch type, in which the wipers move in a forward direction only. Of these switches, the one at the left, switch S, is the sending switch, 30 which counts the impulse trains under control of the registers; while the other one, switch S', is the sequence switch, by means of which the sending switch is placed under the control of the different registers successively. 35 These switches have a special mounting in order to reduce noise and vibration. The switch frames are secured to upper and lower brackets 25 and 26, which are flexibly attached to the main frame plate by means 40 of two pieces of leather 27 and 28.

The relays are mounted in the lower right hand corner and ten are indicated in Fig. 1, although space is provided for eighteen. It will be understood that the number of 50 relays required will depend on the particular circuit used, as will also the spring combinations on the relays. On this account no attempt has been made to show all the relays complete. It will be understood that 55 whatever relays are necessary are mounted in the usual manner with the coil and spring terminals extending to the rear of the frame plate through holes provided for this purpose. The arrangement is believed to be 60 sufficiently indicated in Fig. 1.

The reference letter T indicates a so-called test jack, not mentioned heretofore, which is secured to the front of the frame plate in a manner more particularly shown in Fig. 65 5. The complete test jack assembly with

the parts named from top to bottom as they appear in Fig. 5, comprises a busying key for making the director artificially busy, a busy lamp which is lighted while the director is in use, and two jacks by means of 70 which a test set may be connected to the register control and sending circuits.

Passing now to the rear of the frame plate, and referring more particularly to Fig. 2, the distributing frame will be explained briefly. This comprises two pin boards 30 and 31, of wood or other insulating material, and eleven bus bars 32, which are separated by insulation strips 33 and clamped between the two pin boards. The 75 clamping is effected by means of three bolts 34, 35, and 36, which hold all the parts firmly together. Each of the bus bars is provided with projecting pins or terminals which line up with the rows of pins on the 80 two pin boards. The distributing frame is attached to the frame plate by means of two brackets 37 and 38, seen most clearly in Fig. 3, and a bolt 39 which extends through both brackets and the distributing frame. 85 This arrangement provides a hinge, permitting the distributing frame to be rotated outward away from the main frame plate as shown in Fig. 3, so that ready access may be had to the rear of the director, or rather to that portion of it which is normally covered up by the distributing frame. In order to hold the distributing frame against 90 turning on its hinge except when desired a small bracket 40 is provided, secured by 95 bolt 34 at one end and by a machine screw to the main frame plate at the other end.

The pin boards are used for terminating the conductors coming from the banks of the office register J. There are four hundred of these conductors (switch J having four wipers) which pass through the frame plate in two cables. After reaching the distributing frame these cables are split and formed into two other cables which are 100 fanned out on the upper and lower pin boards in sets of four. Perforated fibre spreaders 41 and 42 are provided. On leaving the cable each set of four conductors goes through an opening in the adjacent 105 spreader, after which the conductors are pulled tight around the front edge of the spreader, Fig. 2, and are soldered to the proper set of pins. The order in which the 110 different sets of conductors are fanned out makes no particular difference, but it may be stated that according to the scheme adopted sets 11-36, inclusive, are terminated at the upper left hand portion of the frame, Fig. 2; sets 37-50, inclusive, are 115 terminated at the upper right hand portion; sets 61-86 are terminated at the lower left hand portion; while sets 87-100, inclusive, are terminated at the lower right hand portion. 120 125 130

The eleven bus bars shown are the digit stop bus bars, the "skip" bus bar, and the director cut off bus bar. The first nine counting from the top are the digit stop bus bars and are connected in multiple to the bank contacts of the digit registers M_1 to M_9 , inclusive, and to the bank contacts of the sending switch S . The next bus bar down is the "skip" bus bar and is connected to the driving magnet of the sequence switch S' , to provide for advancing the sequence switch automatically in cases where less than the maximum number of office code digits are to be transmitted. The last bus bar is the director cut off bus bar. This one is usually connected to a relay which brings about the release of the director under certain circumstances.

A close check on the number of pins in the two pin boards will show that there are two extra sets at the right, which are not required for the conductors from the banks of the office register. These two extra sets of pins are used to terminate conductors coming from spring contacts on special relays such as the "dead number" relay or the "0" operator relay. Other extra sets of pins may be provided of course when needed.

The wires coming from the office register are connected to the pins close up to the pin board so as to leave the ends of the pins free for attachment of jumpers. These jumpers are run vertically in the spaces between the vertical rows of pins, those coming from the upper pin board extending downward to the proper bus bars, while those coming from the lower pin board extend upward and may overlap those from the upper pin board in some cases. In order not to confuse the drawing only one set of jumpers is shown, but this is sufficient to explain what is done.

It has not been considered necessary or desirable to show all the wiring between the various switches and the wiring on the individual switches themselves; in fact this would be very difficult if not impossible. A few of the main cables have been shown, however. The bank cables extending between the office register and the distributing frame have already been pointed out. Cable 50, Figs. 2 and 3, contains the conductors from the special relays and the conductors for connecting up the distributing frame bus bars. Cable 52 contains the conductors extending to the director jack. Cables 53 and 54, Fig. 1, are composed of wires terminating in the sending and sequence switches S and S' . Other minor cables are indicated but need not be described, as it will be understood that the wiring in general follows standard practice.

In order to protect the wiring at the rear of the director, consisting mostly of the connections to the relays and the minor switches,

a cover plate 55, Figs. 2 and 4, is provided. This cover plate is secured at the left by small machine screws as shown, and at the right by two clips such as 56, Fig. 2. Only one clip can be seen as the other is concealed behind the distributing frame. A front cover (not shown) is also provided. This is shaped like a box and is deep enough to enclose all the apparatus in front and have its edges resting against the main frame plate. In order to hold the front cover in position eight bolts or studs 57 are provided. These project out from the face of the frame plate and are tightly engaged by the ends and corners of the front cover, which is thus held in place by friction. An opening in the cover is provided which is closed by the escutcheon plate of the test jack assembly T when the cover is in place. This gives access to the test jack and busy key without removing the cover.

Directors such as the one herein described are intended to be installed on shelves or racks like ordinary Strowger selector or connector switches. This may be explained in connection with Fig. 6. The usual uprights are provided connected by pairs of horizontal angle irons such as 60 and 61, only small sections of the latter, or enough to provide mounting space for one director, being shown. To each pair of horizontal angle irons vertical members such as 62 and 63 are secured by welding or riveting, these members being spaced apart a distance equal to the width of a director. Each vertical member has three pins such as 64 extending clear through and projecting on both sides. These pins are for hanging the directors on the shelf or rack and are engaged by curved slot such as 66, Figs. 3 and 4, in the vertical angle irons of the director frames. Between each pair of vertical members such as 62 and 63, or at each director mounting space, the lower horizontal angle iron carries a female jack as shown in Fig. 6 which is engaged by the male jack of the director, Fig. 2, when the director is hung in place. The method of mounting described makes it possible to quickly and easily remove a defective director and replace it with a good one.

Reference has been made hereinbefore to application Serial No. 547,866 which discloses the circuits and describes the operation of a director of the general type disclosed herein. The circuits of the prior application, however, do not conform strictly to the physical apparatus as herein disclosed in all details. For instance, in the prior application a plurality of skip bus bars are used whereas the present case only shows one. Again, the prior application shows a sequence switch having four wipers, whereas only three are shown on the sequence switch disclosed herein. For a full disclosure of

suitable circuit arrangements, therefore, reference is made to my pending application Serial No. 663,058, filed September 17, 1923, and to the pending application of Bellamy et al, Serial No. 659,304, filed August 25, 1923.

In order to facilitate the understanding of my invention I have described in considerable detail a certain concrete embodiment 10 of the invention, but it will be understood that this was intended merely by way of example, and that the invention is not to be limited to the particular form shown and described.

15 What I consider to be new, therefore, and desire to have protected by Letters Patent will be pointed out in the appended claims.

What I claim is:—

20 1. A director comprising a frame, registering, translating, and sending apparatus mounted on said frame, a jack for connecting the director with a trunk circuit, and permanent wires and cables connecting the pieces of apparatus on said director with each other and with said jack.

25 2. A director comprising a frame, registering and sending apparatus mounted on one side of said frame, and a distributing frame mounted on the other side of said frame.

30 3. A director comprising a frame, an office register, digit registers, and a sending switch all mounted on one side of said frame, a distributing frame mounted on the other side of said frame, and cables connecting the bank of said office register with said distributing frame.

35 4. In a director, a main frame, an office register and a sending switch mounted on said frame, a distributing frame comprising sets of terminals and a plurality of bus bars, cables connecting said sets of terminals with the banks of said office registers, and

another cable connecting said bus bars with said sending switch.

5. In a director, a main frame, a distributing frame comprising two terminal boards spaced apart and hinged to said main frame and a plurality of bus bars positioned between said terminal boards where they can be reached by jumpers coming from either 50 terminal board.

6. A distributing frame for directors comprising two terminal boards, a plurality of insulated bus bars clamped between said terminal boards, cables having their various 55 wires connected to the terminals of the terminal boards, and jumpers for connecting said terminals to said bus bars.

7. A mounting frame for a complete director comprising means for attaching the frame to a rack, mounting spaces on one side of said frame for mounting register sender and sequence switches, and a plurality of relays, and means on the other side of said frame for mounting a distributing frame, 60 said mounting frame having suitable openings where needed for passing the various cables and wires from one side of the frame to the other.

8. In combination with a director, a distributing frame, cables connecting the director to certain terminals of the distributing frame and jumpers connecting wires of said cables to other terminals of the distributing frame. 70

9. A support, a director comprising registering, translating, and sending apparatus mounted on said support, a distributing frame also secured to said support, and cables connecting said registering apparatus 80 with said distributing frame.

In witness whereof, I hereunto subscribe my name this 3d day of June, A. D., 1924.

MARTIN L. NELSON.
